UNITED STATES PATENT OFFICE.

CHARLES PARTINGTON, OF CINCINNATI, OHIO, ASSIGNOR TO THE CINCINNATI FROG & SWITCH COMPANY, OF CINCINNATI, OHIO, A CORPORATION OF OHIO.

SWITCH-STAND.

1,391,208.

Specification of Letters Patent. Patented Sept. 20, 1921.

Application filed July 9, 1920. Serial No. 394,999.

To all whom it may concern:

Be it known that I, CHARLES PARTINGTON, a citizen of the United States, and residing at Cincinnati, in the county of Hamilton and State of Ohio, have invented a new and useful Improvement in Switch-Stands, of which the following specification is a full disclosure.

This invention relates to parallel-throw switches, particularly adapted for use in mines where the clearance between the track and the adjacent walls is small and where, as a result of that condition, it is necessary to mount the switch-stand close to the track in order to allow for the proper throw of the switch-lever.

An object is to provide a positive toggle connection between the switch-lever and the connecting rod for the switch points.

20 Additional objects are to provide for the automatic throw of the switch through the interaction of the wheel flanges with the switch points, and to provide means whereby the center of gravity of the switch lever
25 will remain in such a position with respect to the pivot of a throw-regulating lever that the said switch lever will, when the train or car approaches slowly, operate the switch to arrest the movement of the said switch
30 lever and its connected weight at such a position as will permit the switch points to automatically resume their initial position when a train or car has passed, or in the case where the train or car is moving at a rapid
35 rate to provide for the positive and automatic throw of the switch lever, to operate the switch points and maintain the same in set position, whereby they can only be changed by the manual operation of the
40 switch lever.

Other objects and certain advantages will be pointed out in the specification and special reference is made to the drawings, in which:

45 Figure 1 is a plan view of a turn-out, showing my invention installed and connected with the switch-points of the same. Fig. 2 is a detail top plan of the switch-stand.

50. Fig. 3 is an elevation taken from the lever side of the same.

Fig. 4 is a perspective view of the switch-stand viewed from the lever side.

Fig. 5 is an underneath perspective view of the stand.

Fig. 6 is a detail perspective view of the throw-regulating lever.

The numeral 1, 1 designates the fixed rails, 2, 2, the switch-points or rails, and 3 the connecting rod attached to and connecting the movable switch rails 2. The ties 4 are extended to provide a seat for the switch base plate 5, of angle-iron, formed as shown, to provide a horizontal portion 5^a for attachment to the ties 4, and a vertical portion 5^b for the support of the switch-throwing lever 30. Mounted upon the under side of the portion 5^a, of the base plate 5, is a bell-crank lever 6, pivoted as at 7, upon boss 8, depressed from base portion 5^a of the base plate 5. The arm 9 of said lever has a pivotal connection as at 10 with the connecting-rod 3. The bell-crank lever 6 is of laminated construction, being formed of two sections 11, (as sheet metal stampings), connected together and spaced apart by a spacing plate or disk 12, the arms 13 of the sections 11 having opposed offset portions 14, between which a pivot-block 15, of a toggle means, is connected by a pivot or screw bolt 16. A pair of companion links 17 are attached at one end to the pivot-block 15, by a pivot 18, the said pivot 18 being at right angles to the pivot 16. The opposite ends of the links 17 are pivotally attached, as at 20, to a pivot-block 21, similar in construction to the block 15, and the said block 21 is pivoted as at 22 between the right angle extensions 23 and 24 of a throw-regulating lever 30. This lever 30 is of stamped construction and is formed with a base 31, having upturned edge flanges 32, the said flanges 32 being parallel at their lower portions 33 and symmetrically flared at their upper portions 34, at an angle of 30°, for a purpose hereinafter described.

The base 31, of the lever 30, at the end beyond the edge flange, is bent to form the extension or ear 23, and a stamped pivoting section 36 is fastened, as at 37, between the upturned flanges 32 and below the flared portions 34 of the said flanges, and provides the horizontal extension 24, and an offset vertical portion 38, provided with an opening 39, in horizontal alinement with an opening 40, of the base 31, both for the reception of a pivoting bolt 41, passing through the lower end of the switch lever 42, weighted as at 43, and placed between 100 105 110

the offset portion 38 and the base 31. The bolt 41 extends through the base 31 and through a pressed-out boss 45, of the vertical portion 5^b of the base plate 5, to pivotally connect throw-regulating lever 30 and its switch lever 42 thereto.

The automatic operation of the switch is as follows:

When the switch points or rails 2, 2, are set as shown in Fig. 1, and a train approaches slowly from the direction indicated by the arrow along the portion of the track 50, the wheel flanges will engage at the point 51 between the switch-point 2 and the fixed rail 1, 15 to throw the points 2 in the direction of the arrow. The connecting rod 3, attached to and spacing the said points 2, 2, will be moved to turn the bell crank lever 6. Through the toggle means, connecting the bell crank lever with the switch-throwing lever, the said switch-throwing or hand lever will be brought to a position in which the inside surface 60 of one of the flared flanges 34, (see Figs. 3 and 4), will act to 20 bring the lever 42 and its weight 43 to a position in which the center of gravity of the said lever and weight will be arrested at a point to the right or short of the center line indicated at 61 but near to it, at which 25 time the switch points will be completely thrown, the flange of each oncoming wheel acting successively to maintain the switch points in their open position until the car or train has passed the same, after which 30 the weight will act to bring the said points to their initial position. When, however, the train or car moves at a greater rate of speed, the switch lever is given sufficient momentum to carry its center of gravity beyond the vertical line 61, swinging the lever to an opposite side to positively lock the switch points 2 against the rail 50^a of the main line.

The switch rails therefore can be moved from one position to a second by the wheels of the moving cars and automatically returned as a spring switch after the cars have passed the switch or are maintained in their throw-over position depending upon the rate of speed at which the cars pass the switch. The switch rails may then be set, say closing the main line rails to the siding and by passing the switch rails at a low rate of speed from the siding rails onto the main line rails, the switch rails are moved by the wheels to properly position them for the main line entrance, returning automatically after the cars of the train have passed onto the main line rails to again close the switch rails to the siding against any cars moving in an opposite direction. Moving the cars at a second or higher rate of speed over the switch rails, results in the wheels of the cars striking the right switch rail under an

impact, which will forcibly move the switch 65 rails to the left and thereby transmit or impart an accelerated motion to the switch-throwing parts, moving the switch lever 30 at a velocity which will carry its weighted end beyond its dead central or neutral position to an opposite switch-throwing position, locking the switch, with the siding rails open to the main line rails, so that the cars can be returned to the siding rails without requiring a manual operation of the 75 switch.

The switch connections between the connecting rod and throwing lever provide for permanent pivotal connection as distinguished from any lost motion or loose connection, which would be readily injured by heavy or repeated shocks or jars, and interfere with a free and easy manual throwing of the switch.

The method of connecting the switch lever 85 and switch rail connecting or actuating rod provides a flexible coupling for a switch lever throwing in a line parallel to the rails of a simple, compact and durable construction.

Having described my invention, I claim:

1. A device of the class described, an angle base plate, a lever pivoted to the under horizontal side of said plate on a vertical axis, a lever pivoted on the vertical side 95 of said plate on a horizontal axis, and a connecting link between said levers, its opposite ends having a universal coupling connection with the lever to which it connects.

2. A device of the class described, a base member, a pair of levers pivoted upon said base member with their axes at right angles to each other, and a connecting link between said levers, its opposite ends each having a universal coupling connection with the lever 100 to which it connects.

3. A device of the class described, a base member for supporting the switch throwing members, a bell crank lever pivotally supported upon the base member, adapted to be 110 connected to the switch rails, a two-part switch-throwing lever, one part pivotally supported upon said base member and the second part pivotally mounted upon the said first part, and a connecting link between said 115 bell crank lever and two-part switch-throwing lever, its opposite ends each having a universal coupling connection with the lever with which it joins.

4. In a switch-stand, an angle plate base member adapted to be mounted longitudinally parallel with the rail to be operated, a bell crank lever pivoted upon the base flange of said angle plate base member, adapted to be connected to the movable 125 switch rails, a manually operable lever pivoted upon said base member upon a fulcrum, having its axis at right angles to the

axis of the fulcrum of said bell crank lever, and connecting means having two fulcrum connections with each of said levers.

5. In a switch-stand, a base member, a pair
5 of levers pivoted upon said base member, each upon an axis relatively at right angles to the other, coupling means for connecting said levers, one of said levers connecting with the switch rails and the second formed
10 of two parts, one part joined to said coupling means and the second part pivotally connected upon the first part and adapted to swing thereon within the confined limits upon opposite sides of a central radial line
15 of said parts.

6. In a switch-stand, a base, a lever pivoted on said base for connection with the

switch-rails, a switch-throwing lever pivoted on said base to swing on an axis at right angles to the axis of said first-named lever, 20 link coupling means connecting said lever and having a universal connection with each lever, and an end weighted extension pivotally mounted upon said switch-throwing lever, having a limited independent arc of 25 movement thereon at opposite sides of a central line through said switch-throwing lever.

In witness whereof, I hereunto subscribe my name, as attested by the two subscribing witnesses.

CHARLES PARTINGTON.
